FOREIGN PATENT DOCUMENTS

GB 9005318136-0001 * 6/2018

Primary Examiner — Cynthia Ramirez

Assistant Examiner — Carrie A Matteoli

(74) Attorney, Agent, or Firm — Jason T. Daniel, Esq.;
Daniel Law Offices, P.A.(57) CLAIM

The ornamental design for a pillow, as shown and described.

DESCRIPTION

FIG. 1 is a perspective view of my design for a pillow;

FIG. 2 is a front elevation view thereof;

FIG. 3 is a bottom side view thereof;

FIG. 4 is a top side view thereof;

FIG. 5 is a left view thereof; and,

FIG. 6 is a right view thereof.

The broken lines present in the drawings are for the purpose of illustrating portions of the pillow which form no part of the claimed design. Additional broken lines represent environment and form no part of the claimed design.

1 Claim, 4 Drawing Sheets(56)
